UNITED STATES PATENT OFFICE.

HENRY H. THORP, OF CLEVELAND, OHIO.

IMPROVEMENT IN INK-FOUNTAINS.

Specification forming part of Letters Patent No. 123,651, dated February 13, 1872.

SPECIFICATION.

I, HENRY H. THORP, of Cleveland, in the county of Cuyahoga and State of Ohio, have invented Ink-Feeder for Printing-Presses, of which the following is a specification:

This invention relates to an ink-fountain and feeder for supplying ink to printing-presses having revolving-disk ink-distributing tables, which is constructed and operated as follows:

In the drawing, Figure 1 is a top or plan view. Fig. 2 is a side view. Fig. 3 is a detached view of the lever which operates the ink-feeding roller. Fig. 4 is a section through line $x x$ of Fig. 1. Fig. 5 is a section through line $y y$ of Fig. 2.

A, Figs. 1 and 2, is a box or reservoir for containing ink, which is supported by a bracket, B, that may be attached to the frame of the press which carries the disks. The end of the reservoir A toward the disk is made open, and into which is fitted a feed-roller, C, the journals of which have their bearings in suitable boxes cast in the sides of the box A, the journal on one side extending through and having attached a ratchet-wheel, D. Playing on the same journal is a lever, E, having an oval-hole, e, through it, and diagonally across it, which

allows it to be lifted slightly when the lever is moved backward, to allow the inclined tooth or pawl f on its upper end to pass over the teeth on the wheel D. The journal-boxes have upright projections g g , through which are placed diagonally set-screws h h , which bear upon Babbitt-metal caps i i placed over the journals. The caps i i are held in place by the screws h h , which, standing in a diagonal line over them, permit them to be readily removed when desired. The tops of the caps have a groove in them, which forms a convenient oil-cup.

I claim—

1. The projections g g , the set-screws h h , and the caps i i , when constructed and combined with the feed-roller C and the reservoir A, substantially as described, and for the purpose set forth.
2. I claim the lever E, having a diagonal opening, e , and a hook, f , and the ratchet-wheel D, in combination with the feed-roller C, as and for the purpose set forth.

H. H. THORP.
